UNITED STATES PATENT OFFICE.

SAMUEL S. AMDURSKY AND SAMUEL RUBENFELD, OF ROCHESTER, NEW YORK.

MACHINE FOR CUTTING BUTTONHOLES.

1,316,215.

Specification of Letters Patent. Patented Sept. 16, 1919.

Application filed September 13, 1917. Serial No. 191,320.

To all whom it may concern:

Be it known that we, SAMUEL S. AMDURSKY and SAMUEL RUBENFELD, citizens of the United States, residing at Rochester, in the county of Monroe and State of New York, have invented certain new and useful Improvements in Machines for Cutting Buttonholes, of which the following is a specification.

10 The object of this invention is to provide a new and improved machine for cutting buttonholes.

This and other objects of the invention will be fully illustrated in the drawings, 15 described in the specification and pointed out in the claims at the end thereof.

In the drawings,

Figure 1 is a top plan view of the machine partly broken away.

20 Fig. 2 is a front elevation of the machine partly broken away.

Fig. 3 is a sectional elevation, the section being taken on the line 3*-3* of Fig. 2.

25 Fig. 4 is an end elevation of the machine viewed from the left hand end of Figs. 1 and 2.

Fig. 5 is an end elevation of the machine viewed from the right hand end of Figs. 1 and 2.

30 Fig. 6 is a rear elevation of the machine partly broken away.

Fig. 7 is a detail view of the cutting block and support therefor partly broken away.

35 Fig. 8 is a sectional view through an adjusting device, the section being taken on the line 8*-8* of Fig. 1.

Fig. 9 is a vertical section through one of the cutters, the section being taken on the line 9*-9* of Fig. 1.

40 Fig. 10 is a sectional view of the rear end support of the threaded shaft that controls the spacing of the cutters.

In the drawings like reference numerals indicate like parts.

In the drawings reference numeral 1 indicates the plate at the right hand end of the machine and reference numeral 2 indicates the plate at the left hand end of the machine.

50 On top of these plates and connecting them is the cover plate 3. This cover plate is fastened to the end plate 2 by screws 4, 5 and 6 and to the end plate 1 by the screws 7, 8 and 9.

55 Fastened at the front of the cover plate 3 by the screws 11, 11 is the plate 10. Formed

on the bottom of the cover plate is the flange 12 which with the plate 10 forms a guide or runway for the bearing blocks 13. One of these bearing blocks 13 is provided for each 60 set of cutters in the machine. The cutters are adjustable so that the space between the cutters can be varied uniformly at will and the means by which this result is secured will now be described as follows: 65

Mounted in each of the bearing blocks 13 is a support 14 for the cutters 15 and 16. This support is made up of a round stem 17 and a block 18. The stem 17 makes engagement with the cylindrical opening in the 70 block 13 in which it is free to rotate. Extending rearwardly from the stem 17 as shown in Fig. 1 is a shaft 19 making threaded engagement with the stem 17. On the rear end of the shaft 19 is a knurled wheel or 75 handle 20 by which the shaft 19 and the support 14 may be turned and held in different positions.

For this purpose the shaft 19 is recessed as indicated at 21. Fastened to the shaft 80 19 is the stud 23, the forward end of which makes threaded engagement with the recess in the shaft 19. Mounted on the stud 23 is the flanged collar 22, the small end of which engages in the slot 24 in the rear side of the 85 cover-plate 3. This slot 24 extends substantially the full length of the cover-plate and the shaft 19 and parts attached thereto are free to slide along the slot.

The studs 23 are slotted as indicated at 25. 90 A pin 26 is fastened in each of the handles 20 and makes a sliding engagement with the slot 25 in the stud 23. The handle 20 is normally pressed to the right into engagement with the plate 3 as shown in Fig. 8 95 by means of the compression spring 27, which spring bears against the handle 20 at the right hand end and against the pin 28 fastened in the stud 23 at the other end.

The handle 20 has its forward end recessed to form shouldered parallel sides thereon, which sides normally engage in the slot 24, being held in such engagement by the spring 27. The shaft 19 can be turned 100 by means of the handles 20 so as to throw the cutters into and out of operative position. By withdrawing the handle 20 from the position shown at the right of Fig. 1 the shaft 19 can be turned 180°, after which the handle can again engage in the slot 24 105 locking the shaft in the new position. By means of this arrangement the handle can 110

be held in locked engagement with the slot in the plate 3 in either of two positions 180° apart and the shaft and cutters thereon will be positioned accordingly.

5 On the end of the shaft 19 is the support 14 carrying the cutters 15 and 16 as above described. As shown in Figs. 3 and 9 these cutters are normally positioned with their cutting edges turned down facing the cutting block 29. This cutting block is mounted on the brass cutting block support 30 which moves up and down in a curved path with a parallel movement, it being supported for this purpose by the swinging 15 parallel links 31 and 32. This support is raised by the cranks 33 keyed to the shaft 34, which shaft is rocked by the lever 35 to which is connected a link 36 which in turn may be operated by a treadle or any 20 other suitable device.

As the cutting block approaches the knives by a swinging motion and the material is interposed between the cutting block and the knives, the knives will give a shearing cut to the material causing it to be 25 easily cut by the knives.

By turning the particular ones of the handles 20 one or more of the cutters can be turned away from the cutting block so 30 that those particular knives will not cut the material that is laid on and carried upward by the cutting block. The cutter 15 is circular and is intended to cut the eye at the end of the buttonhole. This cutter is adjustable up and down and for this purpose is mounted on a screw 37 which has a round head at the upper end by which it may be turned up and down in the block 18. The cutter 16 is also adjustable up or 40 down and for this purpose the screw 38 is provided. To prevent the cutter from moving up and down with the screw I support the cutter as follows:

The screw 38 is recessed and receives in 45 its recess the end of the stem 39. This stem makes a shouldered engagement with the bottom of the screw 38 and is provided with a screw 40 which makes a shouldered engagement with the screw 38 near the top 50 thereof, by which the stem 39 can be rigidly clamped to the screw 38. By turning the screw 40 the screw 38 is released from the stem 39 so that the screw 38 is free to turn thereon and as it turns it is raised 55 or lowered in the block 18 and after its desired setting is secured the screw 40 can be turned causing the stem 39 to be moved if necessary and fastened in the desired position. The bottom of the stem 39 is slotted 60 and in the slot is set the knife 16, in which slot it is clamped by the screw 41. The stem 39 is slotted vertically at 42. A screw 43 is provided in the block 18 which has a reduced end which engages with the 65 slot 42 and permits the stem to slide up.

and down but prevents it from turning as the screw 38 is turned.

It will be seen that the end of the cutter 16 comes very close to the cutter 15 so that the slot and the eye of the buttonhole will 70 be cut in substantially one continuous cut, the fiber that is left uncut being little or nothing.

It will be also understood that the cutter 16 cuts a single slit without removing 75 material from the cloth while the cutter 15 cuts a round opening which causes the removal of some of the material from the cloth, which material is pushed upward through the opening in the screw as it accumulates.

The length of the buttonhole is determined by adjusting the cutting block 29 forward or back. This adjustment is secured by the screw 44, which screw makes 85 threaded engagement with the block 29 as indicated at 45 in Fig. 7 and rotates freely in the flange at the front of the support 30 in which it is held against endwise movement. As the cutting block 29 is moved 90 to the right in Fig. 3 it will engage more and more with the cutter 16 and increase the length of the cut.

The ends of the cutting block 29 are guided by the rollers 46 which are set on 95 pins fastened in the upturned ends of the cutting block support 30. Each end of the cutting block will be in engagement with two or three of these rollers and by this engagement the cutting block will be 100 held to a parallel forward and back movement and it will be thereby held in line.

The cutters are spaced apart by a mechanism which we will now describe.

A series of lazy tongs 55 is provided, 105 which lazy tongs on one side are fastened to the bearing blocks 13 and on the other side to blocks 56 which are mounted to slide on the shaft 19. Where the lazy tongs cross they are fastened to blocks 57 which 110 are mounted to slide freely on the screw shaft 58. A double set of these lazy tongs is provided engaging with both the top and bottom of these blocks. At the left hand end of Figs. 1 and 2 the block 57 is threaded 115 and makes engagement with the screw 58. On the right hand end of the shaft 58 is provided a pinion 59 with which meshes a gear 60 which is turned by a crank 61 and a handle 62. By this mechanism the shaft 120 58 can be rotated and the block at the left hand end of the shaft can be moved to the right or left. This in turn will bring the center of all the lazy tongs nearer together or spread them farther apart bringing the 125 shafts 19 closer together or spacing them farther apart. The end shaft is moved the greatest distance and each of the remaining shafts and their cutters are moved to an extent proportional to its distance from the 130

end of the series. It will be understood that all the blocks 57 except the end block slide freely on the shaft, the block at the left hand end alone being threaded to the shaft. The shaft 19 at the right in Fig. 1 and its cutter is held stationary.

As the lazy tongs 55 swing the blocks 57 will be moved forward or back and must, therefore, carry the shaft 58 forward or back with them and to permit this the shaft is mounted to move laterally. To permit the lateral movement of the shaft 58 the end plate 2 has a slot 63 therein which receives the left hand end of the shaft, in which slot the end of the shaft may slide and turn freely. The plate 1 at the right hand end of the machine is provided with a slot 64, in which slot is mounted a block 65, which block carries the end of the shaft 58 and the shaft 66 on which is mounted the gear 60 and the crank 61.

For the purpose of positioning the buttonholes at the proper distance from the edge of the cloth we provide a gage 67 which is adjustable forward and back toward the cutters. The gage is U shaped and the upturned ends 68 and 69 of it are slotted as shown in Figs. 4 and 5. On these ends are provided the racks 70 and 71. A shaft 72 is provided having pinions keyed thereon which engage with each of the racks 70 and 71 so that by turning the shaft the pinions are rotated and the racks are moved forward and backward and the gage is moved with the racks. The shaft 72 is mounted to rotate in the bearings in the plates 1 and 2 as appears in Fig. 3.

As the gage is moved in and out it can swing on the shaft and the forward edge 40 of the gage is held in engagement with the cutting block by means of the spring 73 which is fastened at one end to the gage and at the other end to the end 2 of the machine.

On the end plates 2 and 3 is fastened a U shaped guard plate 75 which guard plate is cut away at the top in front, the edges being bent backward as shown at 76 and 77. On the ends of the guard plate at the top 50 are formed flanges 78 and 79 in which is supported a glass cover plate 80 which protects the cutters.

We claim.

1. In a machine for cutting button-holes, 55 the combination of a frame, a series of cutters mounted to slide thereon, a series of lazy tongs connecting said cutters, a screw shaft, the end pair of lazy tongs making threaded engagement with said shaft, the 60 other pairs of lazy tongs making sliding engagement with said shaft whereby the end cutter is moved positively on the rotation of the shaft, and each of the remaining cutters is moved to an extent proportional to 65 its distance from the end of the series, said

lazy tongs being held against lateral movement on one side and being free to move laterally on the other side and at intermediate points with the screw shaft.

2. In a machine for cutting buttonholes 70 the combination of a frame, cutters mounted to slide thereon parallel to the work, means for rotating said cutters around a horizontal axis to throw them into and out of operation. 75

3. In a machine for cutting buttonholes the combination of a frame having a guide thereon, a bearing block mounted to travel in said guide parallel to the work, a supporting block mounted to rotate on said bearing block, cutters carried by said supporting block, means for rotating said supporting block in the bearing block and locking it in operative or inoperative positions. 80

4. In a machine for cutting button-holes, 85 the combination of a support, a series of cutters mounted to slide along said support, a series of lazy tongs connected to said cutters, said lazy tongs being fastened against movement at one end, means for positively moving them at the other end, said cutters thereafter normally remaining stationary, and means for moving the work against said cutters, said means including a threaded shaft having a threaded nut thereon engaging and moved by said shaft, said nut being attached to the lazy tongs at the free end 90 of the series, sleeves attached to the intermediate lazy tongs and engaging with said shaft to slide freely thereon, said lazy tongs 95 being held against lateral movement on one side and being free to move laterally on the other side and at intermediate points with the screw shaft. 100

5. In a machine for cutting buttonholes 105 the combination of a supporting block, a round cutter and a straight cutter mounted in said supporting block, said cutters working together to cut two parts of a single opening, screws for positively adjusting said 110 cutters up and down.

6. In a machine for cutting buttonholes the combination of a series of cutters, a cutting block adapted to move toward and away from said cutters, means for supporting said 115 cutting block, said means being adapted to move said block with a parallel motion through the arc of a circle by which a shearing cut will be given, said block remaining in all positions parallel to its original position. 120

7. In a machine for cutting buttonholes the combination of a cutting block mounted to swing toward and away from the cutters, a gage mounted to swing on said machine 125 with or independently of the cutting block, said gage bearing against the cutting block and normally swinging therewith.

8. In a machine for cutting button-holes, 130 the combination of a support, a series of cut-

- ters mounted to move along said support, a shaft connected to each cutter by which its movement is controlled, a series of lazy-tongs connected to said shafts, each shaft being connected at two points on opposite sides of the lazy-tongs, said lazy-tongs being fastened against movement at one end, means for positively moving them at the other end, said lazy tongs being held against lateral movement on one side and being free to move laterally on the other side and at intermediate points with the screw shaft.
9. In a machine for cutting button-holes, the combination of a series of lazy-tongs, a series of cutters spread thereby, said cutters having mountings connected to said lazy-tongs on the opposite sides thereof by which said cutters are held in correct parallel alinement, said lazy tongs being held against lateral movement on one side and being free to move laterally on the other side and at intermediate points with the screw shaft.
10. In a machine for cutting button-holes, a series of cutters spread thereby, said cutters having mountings connected to said lazy-tongs on the opposite sides thereof by which said cutters are held in correct parallel alinement, and guides attached to said lazy-tongs at intermediate points by which said tongs are held in alinement at said points, said lazy tongs being held against lateral movement on one side and being free to move laterally on the other side and at intermediate points toward and away from the cutters.
11. In a machine for cutting button-holes, the combination of a series of lazy-tongs, a series of cutters spread thereby, said cutters having mountings connected to said lazy-tongs on the opposite sides thereof by which said cutters are held in correct parallel alinement, said lazy tongs being held against lateral movement on one side and being free to move laterally on the other side and at intermediate points toward and away from the cutters.

10: In a machine for cutting button-holes, the combination of a series of lazy-tongs, a series of cutters spread thereby, said cutters having mountings connected to said lazy-tongs on the opposite sides thereof by which said cutters are held in correct parallel alinement, and guides attached to said lazy-tongs at intermediate points by which said tongs are held in alinement at said points, said lazy tongs being held against lateral movement on one side and being free to move laterally on the other side and at intermediate points toward and away from the cutters.

In testimony whereof we affix our signatures in the presence of a witness.

SAMUEL S. AMDURSKY.
SAMUEL RUBENFELD.
